UNITED STATES PATENT OFFICE.

ORVILLE LINCOLN STORY, OF SOMERVILLE, MASSACHUSETTS.

DESIGN FOR A PAPER-CUTTER, &c.

SPECIFICATION forming part of Design No. 30,977, dated June 13, 1899.

Application filed May 13, 1899. Serial No. 716,747. Term of patent 7 years.

To all whom it may concern:

Be it known that I, ORVILLE LINCOLN STORY, a citizen of the United States, residing at Somerville, in the county of Middlesex and State of Massachusetts, have invented and produced a certain new and original Design for a Paper-Cutter or other Similar Article; and I do declare the following to be a full, clear, and exact description of the invention, such as will enable others skilled in the art to which it appertains to make and use the same.

The invention relates to a new and original design for a paper-cutter or other similar article—a device which combines within one simple and inexpensive article a paper-cutter, envelop-opener, and letter-scale.

In the drawings, Figure 1 is a perspective

view of the device, and Fig. 2 is a top plan view.

The leading feature of the design comprises a tapering blade 1, downwardly-extending points 2, and a handle 3, having transverse slots 4 arranged at different points in its length.

What I claim is—

The design for a paper-cutter or other similar article, as herein shown and described.

In testimony whereof I have hereunto set my hand in presence of two subscribing witnesses.

ORVILLE LINCOLN STORY.

Witnesses:

WILLIAM MULLIN,
JOSEPH J. GILES.
